LOUDEN MACHINERY COMPANY, OF FAIRFIELD, IOWA, A CORPORATION OF IOWA.

CATTLE-STANCHION.

1,194,199.

Specification of Letters Patent.

Patented Aug. 8, 1916.

Application filed June 5, 1914. Serial No. 843,272.

To all whom it may concern:

Be it known that we, WILLIAM LOUDEN and ALBERT H. NELLER, citizens of the United States, residing at Fairfield, in the 5 county of Jefferson and State of Iowa, have invented a new and useful Improvement in Cattle-Stanchions, of which the following is a specification.

Our invention relates to cattle stanchions 10 which may be adjusted in width and it consists of improved means for making said adjustments, whereby the stanchion will be more reliable and symmetrical as well as more sanitary in its construction. Also, of 15 other features set forth in this specification and more definitely defined in the claims.

Referring to the drawings which form a part of this specification, Figure 1 is a side view of a stanchion in closed position embodying our invention. Fig. 2 is the same 20 in open position. Fig. 3 is an enlarged side view of an upper portion of the stanchion, some of the castings on the near side being removed and another being partially broken 25 away. Figs. 4 and 5 are enlarged transverse sections on lines 4-4 and 5-5 respectively of Fig. 1. Fig. 6 is an enlarged transverse section on line 6-6 of Fig. 1, looking in the direction of the arrow. Fig. 30 7 is an enlarged top view from 7 to 7 of Fig. 2, looking in the direction of the arrow. Fig. 8 is an enlarged horizontal section on line 8-8 of Fig. 2. Figs. 9 and 10 are detail views.

Referring to the drawings, A and B represent the side bars of the stanchion which are preferably made of pipes or tubing.

C and D represent hinge plates which are made U-shaped in cross section, as most 40 plainly shown in Fig. 6. These castings are each made substantially in the form of a quadrant or a quarter of a circle with the opening of the U on the outer portion of the circle. Their upper ends are vertically disposed and are secured respectively to the lower ends of the side bars A and B by rivets, or in any other suitable manner, while their lower ends are provided with a series of holes spaced apart and located on 45 a substantially horizontal line, as shown by Figs. 1, 2 and 9, the latter being a detached side view of the lower end of the side bar B with hinge plate D attached. The side bars A and B are hinged together by a bolt E passed through either of the holes in the 50 lower ends of the plates C and D. The members C and D are made U shaped throughout and if preferred, may be made of sheet metal bent to form. Their upper ends being open on the outer sides can be 60 readily slipped on the lower ends of the bars A and be expanded or contracted to fit variations in the size of the bars. Their lower ends are rounded and one of the members is adapted to telescope in the 65 other. The entire arrangement of the hinge members is smooth and symmetrical and there is no place for the accumulation of dirt.

The upper ends of the side bars A and B 70 are connected together by means of two plates F and G, made right and left but otherwise substantially alike, and adapted to be secured together so as to have a hollow space between their central and lower portions while their upper edges are brought 75 together to form a housing to keep dirt from getting in between the plates.

H and I are castings secured to the upper end of the side bar A preferably by rivets J. 80 The lower ends of these castings are made to clamp the upper end of the side bar A between them, and their upper ends are adapted to enter and slide in the opening between the plates F and G at one end thereof. The 85 lower inner faces of these plates at this end are preferably provided with inwardly disposed V-shaped ribs K, and the outer faces of the castings H and I are provided with V-shaped grooves to fit over the ribs K. 90 The upper ends of the castings H and I are also fitted with a series of spaced apart holes M, either of which by sliding the castings in the plates F and G so that either of the holes M will coincide with the holes in the plates F and G, that the space between the upper ends of the side bars A and B may be varied. Also, by setting the 95 hinge bolt E in different holes in the hinge pieces C and D, the space between the lower ends of the side bars may be varied, thus 100 making the stanchion either wider or narrower as desired.

The upper end of the movable side bar B. is held in place by means of a latch O pivoted between the plates F and G to engage 110

5 a toothed section P having one of its ends pivoted to castings Q and R secured to the upper end of the side bar B. The central part of the latch where it is pivoted, is open and in this opening a torsion coiled spring S 10 may be mounted on the bolt T upon which the latch is pivoted. One end of the spring is preferably arranged to bear up against the outer end of the latch and the other to bear down against lugs g on the inner faces of the plates F and G. By this means the inner end of the latch will be held in engagement with the teeth of the section P. This section is of less length than the plates 15 F and G and its free end is arranged to slide in the space between the plates.

To regulate the position of the side bar B (when latched) in relation to the plates F and G and the other side bar A, the plates 20 F and G are fitted with a series of holes U in either of which a bolt b may be placed so as to come in contact with the free end of the toothed section P and prevent it and the side bar B (to which it is connected) from 25 approaching nearer to the side bar A. By this means and the other adjustments of the hinge castings previously referred to, the space between the side bars A and B may be regulated as required to suit the different 30 sizes of the cattle to be held by the stanchion. The stanchion will be held securely in whatever position it may be set and cannot be slipped from one position to another which sometimes occurs when any sort of 35 screw is used to make the adjustments.

To prevent the side bar B from being spread too far whereby it might strain or break the hinge castings C or D, inwardly extending ribs V are formed on the inner faces at the ends of the plates F and G 40 adjacent to the bar, and outwardly extending lugs W are formed on the extreme free end of the section P, so as to come in contact with the ribs V, and thus limit the outward movement of the section and also of 45 the side bars B to which it is connected. Also, to make a more reliable connection between the section P and side bar B, and the plates F and G, inwardly extending ribs X 50 are formed on the lower edges of the plates and outwardly extending lugs Y are formed on the extreme lower ends of the section P which are adapted to slide on the ribs X. Outwardly extended lugs or flanges Z are 55 also formed on the outer faces of the castings Q and R which are adapted to slide on the ribs X when the side bar B is closed. These lugs or flanges are preferably set obliquely, as shown, so they will be more certain to catch over and slide on the ribs X.

To save room and make the stanchion more compact, it is preferable to make the end of the section P, which strikes against the bolt b, forked so that the ends carrying 60 the lugs W and Y will pass by the bolt b.

In adjusting the side bars A and B it is essential that they be kept approximately parallel, otherwise the stanchion might become too wide at one end and too narrow at the other. The upper sides of the plates 70 F and G are preferably rounded and inwardly curved as most plainly shown in Fig. 4, so they will meet together throughout the most of their length whereby a neat appearance is presented and dirt and debris is 75 kept from entering the open space between the plates. Some openings, however, are required, one for the mounting of the latch O and one for the insertion of the chain m which connects the stanchion to the holder 80 on the top rail r. At the latter point the plates are extended upwardly and are fitted with inwardly disposed coinciding thimbles or perforated bases around which the lower link of the chain m is placed and through 85 which the bolt a is passed, as shown in Fig. 10 which is an enlarged transverse section of this part of the plates F and G. The chain and the thimble close the most of this opening and the latch O closes the most of 90 the opening in which it is mounted as will be seen by Fig. 7. It is desirable that the plates F and G be made separable so that the heads of the castings H and I and the other internal parts may be more easily inserted or removed and the ends of the spaced apart portions may be closed or partially closed, as desired. The lower stanchion chain n which anchors the stanchion to a 95 lower support (not shown) is connected to 100 the hinge bolt E, as shown in Fig. 6.

The entire arrangement is extremely simple and easily adjusted and operated. Five different adjustments can be made, three of them by making the adjustment on both 105 sides and two of them by making the adjustment on one side.

The castings Q and R may be provided with prongs q to catch around an adjacent stall post to prevent the stanchion from 110 swinging around when open. We do not, however, desire to confine ourselves to the precise construction set forth because a number of changes in the details can be made without departing from the spirit of our invention.

What we claim is:

1. In cattle stanchions, a pair of vertically disposed spaced apart bars hinged together at their lower ends, a pair of separable, horizontally disposed plates having their central and lower portions spaced apart and their upper edges brought together to form a housing, the upper end of one of said bars being secured between the plates under the 120 housing and near one of the ends thereof, and the upper end of the other bar being 125 slidable in the space between the plates, a toothed section of less length than the plates being hinged at one end to the upper end of the 130

slidable bar and its other end arranged to slide between the plates, and a latch to engage the toothed section and hold the bars in closed position.

5. 2. In cattle stanchions, a pair of vertically disposed spaced apart members hinged together at their lower ends, a pair of horizontally disposed plates set side by side with an open space between their central and lower sides, and having inwardly extending ribs near one of the ends thereof, a pair of castings having outwardly disposed recesses adapted to embrace and slide on said ribs, secured to the upper end of one of the members, and having a series of holes in their upper ends, said castings being secured in position by a bolt passed through the plates and through one of the holes in the castings, the other member being slideable between the plates, and a latch mounted between the plates whereby the movable member will be held in closed position.

3. In cattle stanchions, a pair of vertically disposed spaced apart members hinged together at their lower ends, a pair of horizontally disposed plates set side by side with an open space between their central and lower sides, the upper end of one of the members being secured between said plates near one of the ends thereof, a pair of castings secured to the upper end of the movable member and their upper ends slideable between the plates, a toothed section hinged at its outer end to the upper end of said castings and slideable between the plates, a bolt passed through the central portion of the plates to abut the end of the toothed section and prevent it from moving farther inward, and a latch mounted between the plates so as to engage the toothed section, whereby the movable member will be held in closed position.

4. In cattle stanchions, a pair of vertically disposed spaced apart members hinged together at their lower ends, a pair of horizontally disposed plates set side by side with an open space between their central and lower sides and having a series of centrally located holes, the upper end of one of the members being secured between said plates near one of the ends thereof, a pair of castings secured to the upper end of the movable member, a section having a series of teeth hinged at its outer end to the upper end of said castings and slideable between the plates, a bolt inserted in one of the central holes in the plates to abut the end of the toothed section and prevent it from moving farther inward, and a latch mounted between the plates so as to engage the tooth of the section corresponding to the hole where the bolt is set, whereby the movable member will be held in different positions with regard to the other member.

5. In cattle stanchions, a pair of vertically

disposed spaced apart members hinged together at their lower ends, a pair of horizontally disposed plates set side by side with an open space between their central and lower sides, the upper end of one of the members being secured between said plates near one of the ends thereof, a pair of castings secured to the upper end of the movable member, a toothed section hinged at its outer end to the upper end of said castings and slideable between the plates, a latch to engage the toothed section, a bolt passed through the central portion of the plates to abut the end of the toothed section and prevent it from moving farther inward, the free end of the toothed section being fitted with outwardly projecting lugs and the adjacent ends of the plates being provided with inwardly projecting lugs adapted to come in contact with the lugs on the toothed section and arrest its outward movement.

6. In cattle stanchions, a pair of vertically disposed spaced apart members hinged together at their lower ends, a pair of horizontally disposed plates set side by side with an open space between their central and lower sides, the upper end of one of the members being secured between said plates near one of the ends thereof, a pair of castings secured to the upper end of the movable member, a toothed section hinged at its outer end to the upper end of said castings and slideable between the plates, a latch to engage the toothed section, a bolt passed through the central portion of the plates to abut the end of the toothed section and prevent it from moving farther inward, inwardly extending ribs on the adjacent lower edges of the plates and outwardly extending lugs on the lower inner ends of the toothed section adapted to slide on the ribs of the plates.

7. In cattle stanchions, a pair of vertically disposed spaced apart members hinged together at their lower ends, a pair of horizontally disposed plates set side by side with an open space between their central and lower sides, the upper end of one of the members being secured between said plates near one of the ends thereof, a pair of castings secured to the upper end of the other member, a toothed section hinged at its outer end to the upper end of said castings and slideable between the plates, a latch to engage the toothed section, a bolt passed through the central portion of the plates to abut the end of the toothed section and prevent it from moving farther inward, inwardly extending ribs on the adjacent lower edges of the plates and outwardly extending obliquely set lugs on the upper ends of the castings attached to the movable member, said lugs being adapted to catch over and slide upon the ribs on the plates.

8. In cattle stanchions, a pair of verti-

4
cally disposed spaced apart members hinged together at their lower ends, a pair of horizontally disposed plates set side by side with an open space between their central and 5 lower sides, the upper end of one of the members being secured between said plates near one of the ends thereof, a toothed section pivotally connected at its outer end to the upper end of the other member, and a 10 spring pressed latch mounted in an opening in the upper edge of the plates, with its inner end fitted with outwardly extending lugs and adapted to engage the toothed section and hold the movable member in closed 15 position, its other end extended out through the opening in the plates and the lugs adapted to rest on the upper edges of the opening in the plates.

9. In cattle stanchions, a pair of vertically 20 disposed spaced apart stanchion bars having latching means at their upper ends, a

pair of hinge plates bent longitudinally in approximately a quarter of a circle, and U-shaped in cross section, the opening of the U being on the outer portions of the circle, 25 the upper ends of said plates being secured to the lower ends of the stanchion bars, the lower end of one of the plates being constructed to telescope in the lower end of the other plate, and both of said lower ends being fitted with coinciding pivot holes, a pivot member inserted in said holes, and an anchor member connected to the pivot member under the cover of the telescoped ends of the plates. 30
